(No Model.)

D. B. GOTHAM.
STRAINER.

No. 530,586.

Patented Dec. 11, 1894.

UNITED STATES PATENT OFFICE.

DARWIN B. GOTHAM, OF WATERTOWN, NEW YORK.

STRAINER.

SPECIFICATION forming part of Letters Patent No. 530,586, dated December 11, 1894.

Application filed December 8, 1893. Serial No. 493,103. (No model.)

To all whom it may concern:

Be it known that I, DARWIN B. GOTHAM, of Watertown, in the county of Jefferson, in the State of New York, have invented new and useful Improvements in Strainers, of which the following, taken in connection with the accompanying drawings, is a full, clear, and exact description.

My invention relates to improvements in strainers of the class set forth in my United States Patent No. 511,770, granted to me January 2, 1894, and has for its object the production of a simple device, which is extremely strong and rigid, is highly efficient, and continuous in action, operates with a minimum amount of rattling, and is so constructed as to prevent blowing of air through the strained material and consequent displacement thereof; and to this end it consists in the detail construction and arrangement of the parts, all as hereinafter more particularly described and pointed out in the claims.

In describing this invention, reference is had to the accompanying drawings, forming a part of this specification, in which like letters indicate corresponding parts in all the views.

Figure 1 is an isometric perspective of my improved strainer, illustrating the general construction and arrangement of its parts. Fig. 2 is a longitudinal vertical sectional view, partly in elevation, of the upper portion of the strainer, as seen in Fig. 1, and Fig. 3 is a transverse vertical sectional view, taken on line 3—3, Fig. 2.

The frame A of my invention is provided at its opposite ends with standards B B having their lower extremities secured together by longitudinal tie bars C C connected by cross bars c, and said frame A consists of upper and lower sections a a' hinged together at corresponding edges by hinges a³.

The upper section a of the frame A is formed with a vat D for receiving the unstrained material, and at the base of the chamber D is a screen plate d secured to suitable supports as cross bars d' and shoulders d². The unstrained pulp is admitted into this vat D in any desired manner, and, as presently described, passes outwardly through the perforations of the screen plate d.

Beneath the screen plate d is a series of stationary suction chambers E separated by partitions consisting of packing strips e and the cross bars d' directly above said strips, 55 and at the base of the suction chambers are diaphragms E' secured at their edges to the lower walls of said chambers. The diaphragms E' are forced up and down by plungers F, presently described, and by the operation of said diaphragms, a suction is produced in the chambers E, and the unstrained material is drawn from the vat D through the screen plate d into said chambers E.

The strained material passes from the suction chambers E into outlet passages e' e', which extend downwardly from the adjacent edges of each pair of the suction chambers. Beneath each pair of the outlet passages is an outlet chamber G, which extends transversely across the frame A, and is formed with a projecting front end extending beyond the front wall of the frame A and having an opening g in its upper portion. Directly above the outlet chamber G is an upper outlet chamber G' having its opposite ends each provided with an opening g' registering with the two openings g in the outlet chamber G and having its central portion formed with a depending outlet nipple G², whence the strained material is conducted by any suitable construction of piping.

It will be particularly noted that the combined depth of the outlet passage e' and the outlet chamber G communicating therewith is considerably greater than the depth of the suction chamber discharging thereinto, and also that the upper outlet chamber G' forms a liquid seal between the chambers G and the nipple G². This is an essential feature, as, if said parts are otherwise constructed, there is more or less liability of air being blown through the outlet passage and chamber and effecting agitation and displacement of the strained material, and impairing the continuity of its flow. This result is positively prevented by the construction of liquid seal in my present machine, and, in its practical operation, the strained material flows quietly and continuously from the outlet chambers. This is obviously a particularly simple, practical, and effective arrangement of receiving cham-

ber for the unstrained material, suction chambers, outlet passages, and outlet chambers for the strained material.

The plungers F, previously mentioned, are of any desired construction, and are each provided with a plunger rod f having its upper end guided through an upper bearing f' and provided with an encircling coiled spring H having one end resting against the bearing f' and the other against a shoulder f² adjustable lengthwise on the upper end of the plunger rod f, and adapted to be held in position by a check nut f³. The lower end of each of the plunger rods f is passed through and extends beneath a bearing i of a bracket I secured to one of the cross bars c between the longitudinal tie bars C. The lower end of this bracket is provided with an oil chamber i' and with a bearing i² arranged at an angle with the former bearing i.

A shaft I' is journaled in the bearings i², and is provided with cams J each having the lower portion of its engaging face movable in the corresponding oil chamber i' for lubricating said face. The lower end of each plunger rod f is provided with a head f⁴ arranged beneath the corresponding bearing i, and this head is formed with a dove-tail-groove f⁵ aligned with the adjacent cam J and within which is removably secured a lengthwisely tapering wearing piece f⁶ of copper, lignum-vitæ, or other material softer than the engaging face of the cam J. The cams J are arranged so as to operate successively, so as to cause the plungers to move simultaneously and oppositely in pairs, and are each formed with an abrupt incline j for forcing the plungers upwardly at greater speed than the same descend in order to effect cleaning of the screen plate d by the upward movement of the plungers.

It frequently happens that the screen plate of strainers now in use is more or less clogged, and a considerable depth of unstrained material is supported above the same, and consequently an insufficient amount of pulp is supplied to the suction chambers, and, as it is evidently impractical to stop the rotation of the actuating shaft of the strainer, the continued movement of the plungers produces a considerable vacuum within the suction chambers, and thereby causes great strain upon the parts, and frequently fractures or detaches the diaphragms or otherwise injures the strainer. This undesirable result is entirely obviated by my improved strainer, since the plunger rods are entirely disconnected from their actuating cams, and the plungers are forced downwardly by the action of the springs H, only, which are evidently not sufficiently strong to produce an undue vacuum. Indeed, if a vacuum should be produced, the springs are unable to act against the vacuum, and the actuating shaft and the cams carried thereon, revolve freely without engaging the wearing strips or without effecting any strain or injury to the parts,

and particularly of the diaphragms. As soon, however, as the vacuum is disturbed by unclogging the screen plate of the chamber D and the normal supply of strained material to the suction chambers, the springs H force the lower end of the plunger rods, or, more strictly speaking, the wearing pieces f⁶ into engagement with the actuating cams, and straining of the material continues. Except in rare instances, however, no vacuum will be produced in this machine. When a plunger descends—supposing the screen plate above it to be clogged—a partial vacuum is formed within the suction chamber, but the strained material within the outlet passage e' and the outlet chamber G will, by the weight of the material within the upper outlet G', flow into the suction chamber E' and relieve the vacuum forming therein; yet the disposition of the outlet chamber G below the suction chambers E' prevents the blowing of air from one suction chamber to the other; and the fact that the plunger in one chamber rises as the other descends, tends to force material into the outlet chamber G just at the time it is needed to rise through the passage e' into the other suction chamber E' to overcome the vacuum forming therein. All this will take place without, however, permitting any air to enter either suction chamber, because of the water seal formed in the upper outlet chamber G'. This peculiar construction and arrangement of plunger rods, actuating cams, and springs H are also extremely efficient in preventing rattling of the parts, since, even though said pieces f⁶ become considerably worn, the springs H force the same into contact with the faces of the actuating cams, and said parts operate as effectively as though new wearing pieces were in use. This action of the springs H may be facilitated by the adjustment of the movable shoulders f² on the plunger rods. Rattling of the parts and vibration of the actuating or driving shaft I' is also prevented by the extremely rigid construction of support therefor, since the bearings for the driving shaft are separated but a slight distance, are extremely long, are formed integral with the brackets provided with the bearings for the lower ends of the plunger rods, and are rigidly secured upon short cross bars having their opposite ends firmly supported upon the longitudinal bars C C, which are extremely rigid and strong.

It will be evident upon reference to the foregoing description and an examination of the drawings that my invention is simple, extremely strong and rigid, is highly efficient and continuous in action, operates with a minimum amount of rattling, and is so constructed as to prevent blowing of air through the strained material and consequent displacement thereof and to also prevent injury or breakage of the parts.

Having thus fully described my invention, what I claim as new, and desire to secure by Letters Patent, is—

1. In a strainer, the combination of a vat for receiving the unstrained material provided with a screen plate through which the material is strained, stationary suction chambers at one side of said screen plate, a downwardly extending outlet passage opening along contiguous edges of each two adjacent suction chambers, and a single outlet chamber arranged beneath each pair of outlet passages and opening therefrom, substantially as and for the purpose set forth.

2. In a strainer, the combination of a normally stationary vat for receiving the unstrained material provided with a screen plate through which the material is strained, stationary suction chambers each arranged at one side of the screen plate, a downwardly extending outlet passage opening from each suction chamber, an outlet chamber arranged beneath each pair of the outlet passages and

opening therefrom and having one end thereof extending beyond the corresponding wall of the adjacent suction chamber, an upper outlet chamber arranged above the end of the former outlet chambers and having its 25 opposite ends provided with inlets registered with the outlets in the ends of the former outlet chambers, said upper outlet chamber forming a water seal and being provided with an outlet at its central portion, substantially 30 as and for the purpose specified.

In testimony whereof I have hereunto signed my name, in the presence of two attesting witnesses, at Brownville, in the county of Jefferson, in the State of New York, this 35

4th day of December, 1893.

DARWIN B. GOTHAM.
